(57) **CLAIM**

The ornamental design for an electronics cable retail packaging as shown and described.

DESCRIPTION

FIG. 1 is a top plan view of an electronics cable retail packaging;

FIG. 2 is a front elevational view thereof;

FIG. 3 is a bottom view thereof;

FIG. 4 is a left-side elevational view thereof, the right-side elevational view being a mirror image thereof;

FIG. 5 is a rear elevational view thereof;

FIG. 6 is a front isometric view thereof, showing my design being used; and,

FIG. 7 is a rear isometric view thereof, showing my design being used.

(Continued)

The broken lines represent environmental structure and form
no part of the claimed design.

1 Claim, 4 Drawing Sheets
